UNITED STATES PATENT OFFICE.

JOSEF KOLB, OF NEUTITSCHEIN, AUSTRIA-HUNGARY.

MACHINE FOR MAKING THE BATS FOR HATS.

1,128,007.

Specification of Letters Patent.

Patented Feb. 9, 1915.

Application filed June 22, 1914. Serial No. 846,464.

To all whom it may concern:

Be it known that I, JOSEF KOLB, manufacturer, subject of the Emperor of Austria-Hungary, residing at Kaiswr Josefstrasse, 5 Neutitschein, Moravia, Austria-Hungary, have invented certain new and useful Improvements in Machines for Making the Bats for Hats, of which the following is a specification.

10 The present invention relates to a novel machine for making bats for hats whereby the rate of output of such machines is very largely increased.

15 A machine constructed according to my invention comprises means whereby the machine works continuously. In the preferred form of my invention this result is attained by providing the machine with two or more bat forming chambers supplied by a feed 20 device common to them both and also with operating mechanism arranged between the feed device and the bat chambers, this mechanism regulating the access of the material to be formed into bats to the bat chambers 25 in such a manner that it is possible to form the bats in a continuous operation.

The invention is illustrated in the accompanying drawing, in which:

Figure 1 is a longitudinal section of the 30 machine. Fig. 2 is a section showing the construction of a bat forming chamber. Fig. 3 is a horizontal section on the line III—III in Fig. 1. Fig. 4 is a horizontal section of the bat forming chamber on the 35 line IV—IV in Fig. 6. Fig. 5 is a cross-section of the bat chambers on the line V—V in Fig. 3. Fig. 6 is a side elevation of the bat chambers with the whole of the operating and adjusting mechanism of the machine 40 for positively actuating its auxiliary mechanisms. Fig. 7 is an elevation of the machine, and Fig. 8 is a section of a detail of the spraying device in section.

As shown in Fig. 1 the front portion of 45 the machine consists of a hopper device *a* into which the fibrous material (hair, etc.) to be formed into bats is placed, and of a special distributing device *b* for the material supplied to the machine which distributes it uniformly onto appropriate conveyer devices *c*. Behind the conveyer device the suction or atomizing chamber *d* usual in such machines, is arranged; in this chamber

the hair supplied by the conveyer device *c* is broken up into a cloud of hairs. 55

In accordance with the invention, two or more bat forming chambers *f*, *f'* are fitted to the chamber *d*; their charging is regulated by mechanism *s* (Figs. 1, and 3) in a manner hereinafter explained. In each of 60 the bat chambers a bat former *t*, *t'*, and a spraying device *i*, *i'* are arranged. The bat chambers are connected with an exhausting conduit *e* in a known manner and for the known purpose. 65

The charging device for the machine consists of a simple charging hopper *a*. The distributing device *b* consists of two drawing rollers 1, 2 arranged below the charging hopper *a* beneath which a quickly running 70 distributing roller 3 (a picker roller) of very short compact construction revolves (see Figs. 1 and 3). By this distributing roller, the fibrous material is thrown off into the distributing box *b* which flares out 75 sharply in the lateral direction, whereby tufts of fibrous material are broken up and distributed. Owing to the conically flared form of the distributing box *b*, the breaking up and distribution of the fibrous material 80 are rendered exceedingly uniform. This form of distributing box also permits of the employment of a distributing roller of very short compact construction, so that it can be run at very high speeds without producing any harmful self-oscillation. The air currents produced by the quick rotation of the distributing roller 3, are damped by the conically flared form of the distributing box and the sieve-like damping surface 4 (Fig. 90 1) built into it. In the device described, the fibrous material is deposited in a thoroughly uniform finely divided condition on the delivery apron 5, which moves downward carrying the material on to the conveyer apron 95 *c* which conducts the distributed fibrous material to the atomizing chamber *d*. In front of this chamber drawing rollers 8, 9 are provided in the known manner to conduct the fibrous material in a manner known *per se* 100 to a second distributing or picker roller 11 and a so-called blowing roller 13. By means of these rollers 11 and 13 the material is pulverized in a manner known *per se*, that is to say it is broken up or disintegrated by 105 the roller 11, and by air issuing through the

perforations in roller 13 is formed into a finely divided cloud of hairs which in a manner hereinafter explained is positively conducted into one or other of the bat chambers *f*.

In order to prevent the fibrous material from adhering to the drawing rollers 8, 9 strippers 17, 18 are arranged above and below them; in accordance with the invention, 10 these strippers are given a hollow or box-like formation.

Owing to the hollow formation of the strippers any knots which form in the fiber owing to the friction of the fibrous material 15 against the strippers are prevented from reaching the bat chambers, as these knots of hair or "burs" are in the present case collected in the stripper boxes from which they can be removed from time to time. With 20 this object the lower stripper 18 is provided with an opening 18' through which the dust and any knots that may form can drop out. The upper stripper 17 is provided with a tubular socket 17' which can 25 be fitted to a compressed air pipe thereby insuring the blowing out of any foreign bodies accumulating in the stripper box 17.

From the box *d* the broken up fibrous material is drawn into the bat chambers, and. 30 as already stated, the access to these chambers of the material to be formed into bats. is regulated by special mechanism *s*. This mechanism *s* can be formed in any convenient manner without affecting the principle 35 of the invention; in the example illustrated in the drawing, it consists of a pivoted flap *s* secured to a shaft 20 which is operated in some convenient manner (Figs. 1 and 3). An operating arm 21 is keyed on this shaft 40 and is controlled in a manner hereinafter explained.

In accordance with the invention, the reversal of the operating mechanism *s* and also the actuation of the auxiliary devices provided 45 in the bat chambers are effected automatically so that when the formation of a bat is finished in one chamber, the mechanism *s* and the auxiliary devices provided in the bat chambers are positively reversed 50 as is necessary for the bat forming operation in the adjacent bat chamber which is to be recharged. This is effected most simply by coupling the adjusting mechanism of the bat chamber reversing flap *s* and the other 55 auxiliary apparatus with the opening and closing mechanism for the bat chamber doors *r'*, *r''* by means of suitable rods, chains, cables or the like. This method of control can be adapted for the novel machine, be- 60 cause it is well-known that the formation of the bat which takes place when the bat chamber door is closed occupies approximately the same time as the spraying and the removal of the bat from the chamber 65 which takes place when the door is open.

In the embodiment of the invention illustrated in the accompanying drawing this special control of the bat chambers is insured by means of the following devices: As shown in Figs. 2 and 6, the doors *r'*, *r''* of the bat chambers are formed as sliding or rolling doors and are suspended so as to counterbalance each other on a cable or chain 23. This chain is carried by two rollers 24 rotatably mounted on the upright 25. 70 Independently of this chain a second chain or cable 28 (Fig. 5)—the so-called control cable drive—is provided, its path around the bat chambers *f'*, *f''* being shown in Figs. 5 and 7. This cable 28 is fixed at one of its 75 ends to the known draft regulating plate 30' of the bat chamber *f'* and runs over the rollers 31, 32, 33 through the lug 21' of the oscillating arm 21 of the flap *s* and is carried back to the regulating plate 30'' of the second bat chamber *f''* over the rollers 34, 35 and 36. Tappets 40', 41' and 40'', 41'' (Fig. 6) are adapted to be adjusted and fixed upon the cable 28 within operative reach of the doors of the chambers; these tappets 80 are operated in a manner hereinafter explained by the arms 42' and 42'' fixed to the doors of the bat chambers. Moreover on the cable 28 tappets 44 are adapted to be adjusted and fixed within operative reach of 85 the arm 21 of the bat chamber reversing flap *s*; these tappets act on the arm 21 in a manner hereinafter explained.

As already stated, the auxiliary devices provided in the bat chambers, such for example as the spraying devices *i'*, *i''* are rendered operative and inoperative positively by the control devices actuated by the bat chamber doors. With this object each of the spraying devices *i'*, *i''* located in the chambers *f'*, *f''* is connected with a specially formed three-way valve *w* (Figs. 6, 4 and 8) by means of which the access of the water to the spraying devices *i'*, *i''* is controlled. In the embodiment of the invention here 105 illustrated in Fig. 8 this three-way valve consists of two correspondingly formed valve casings 50, 50 connected one with the other by sockets 51. The spraying devices *i'*, *i''* are fitted to the sockets 52; the spraying liquid is supplied through the pipe 53. In each of the valve casings, a spindle 54' or 54'' is arranged each spindle being provided with two valve plates 55', 57'. A control lever 58', 58'' acts upon each of these 110 valve spindles 54' and 54'' respectively; these levers oscillate about a common pivot 59. These control levers 58', 58'' are operated in a manner hereinafter explained by tappets 60', 60'' fixed to the doors of the bat chambers, whereby the supply of 115 spraying liquid can be regulated as desired.

The operation of the apparatus described above is as follows: Assuming that a bat has already been deposited on the former *t'* ar- 120

ranged in the bat chamber f' ; also assuming that the bat chamber reversing mechanism s occupies the position shown in Fig. 3 in which position when the bat chamber door 5 r'' is closed, the forming of the bat takes place in the chamber f'' . In this phase the lever 58' of the spraying liquid three-way valve w , whereby the spraying liquid is sprayed over the path 53, 51, 52, i' on to the bat arranged on the former t' . Accordingly, while the bat forming takes place in the chamber f'' the bat previously formed in the chamber f' is sprayed. After the spraying 10 is finished, the bat is removed from the former t' and at this point the bat forming in the chamber f'' is finished. At this moment the bat chamber door r'' is raised, whereby the entire apparatus is positively 15 reversed. In the first place owing to the upward movement of the door r'' the cable 28 is displaced in the direction indicated by the arrow in Fig. 6 by the striking of the door arm 42'' against the tappet 40'' on the 20 cable. This causes the cable tappet 44 to strike against the arm 21 of the pivoted flap s , thus positively shifting the latter from the position shown in full lines in Fig. 3 into the position shown in broken lines. By this 25 means the bat chamber f'' (Fig. 3) is cut off and the chamber f' is thrown in. At the moment the door r'' is raised, the valve spring 56' of the spraying liquid valve w presses the valve stem 54' downward (Fig. 30 8) thereby suddenly cutting off the access of liquid to the spraying device i' . On the descent of the valve stem 54', the lower valve 57' is opened and the whole of the water that may still be contained in the spraying 35 plate i' is carried off along the path 52, 57', 63.

It will be obvious from Fig. 6, that when the door r'' is drawn upward, the door r' is positively lowered, and owing to the descent 40 of the door r' , the spraying device i'' is positively rendered operative, in the same way, as when the door r' is in the closed position, the tappet 60' strikes the valve control lever 58''. Accordingly, if the bat 45 chamber door r'' is raised and the door r' lowered, the spraying device i'' is cut off while simultaneously reversing the bat chamber mechanism s and the spraying device i'' is rendered operative.

50 As already stated, the movement of the control cable 28 in the direction indicated by the arrow also controls the regulating plate 30', 30'' mounted in the bat formers and known *per se*, these plates being given 55 a position corresponding to the phase of the operation, taking place in the respective bat chambers. When the door r' is closed and the door r'' open, the plate 30' is raised and the plate 30'' is lowered.

55 To permit of setting the regulating plate

at different heights in the bat former, according to the type of bat, the control cable 28 is secured to a collar 71 adapted to be adjusted and fixed on the stem 70' of the plate. This method of fixing the ends of 70 the cable also provides for altering its tension.

The air is drawn through the bat former in the known manner by means of an exhauster 80 (Fig. 7) which is connected by 75 pipes 81, 82 (Figs. 6 and 7) to the base 83 of the chambers f' , f'' . Closing doors 84 are arranged in the pipe 82 and are adapted to be controlled by means of the handle 85 and the rod 86 connected therewith. By 80 means of this device, it is possible in case of need (during the spraying process for example) to connect with one of the chambers the exhauster pipe leading to this chamber.

Above the bat formers t' , t'' plates 90 85 (Figs. 3 and 5) with specially formed recesses 91 are provided to partially cover the bat formers. By suitably forming these recesses 91, the fibrous material is prevented from settling more thickly on the portions 90 of the surface of the former t' adjacent to the device supplying the fibrous material than on the portions of the former distant from the supply device.

The control of the bat chamber operating 95 mechanism, of the chamber doors and of the other auxiliary devices of the machine can be modified as desired without departing from the principle of the invention. Similarly the drive of the conveyer and distributing 100 mechanism can be modified in various ways. In the embodiment of the invention illustrated in the drawing, the distributing and conveyer mechanisms are driven from the main shaft 93 (Figs. 1 and 7), which is 105 driven by the belt pulley 94 mounted on this shaft. The distributing rollers or picker rollers 3, 11 are driven through the belt 95 (Figs. 3 and 7). The conveyer bands are driven by the belt 96 which, through appropriate chain wheel and chain transmissions, rotates the rollers 97, 98 of the conveyer bands. The exhauster is driven through the belt 99 as shown Fig. 1; the mechanism 100 for rotating the bat formers t' , t'' which is 110 known *per se* is driven through the belt 101.

While necessitating but slightly more power the apparatus described above very largely increases the output of bat forming machines as it is possible with a reduced 115 staff and in a shorter working time, to produce a much larger number of bats than with the known bat forming machines comprising a single bat chamber.

Having now particularly described and 120 ascertained the nature of my said invention and in what manner the same is to be performed, I declare that what I claim is:

1. In a hat forming machine, the combination of a pair of juxtaposed bat forming 125

- chambers, feeding mechanism common to both said chambers, means common to both said chambers whereby either thereof may be cut off from communication with said feeding mechanism, and means for automatically operating said first named means.
5. In a hat forming machine, the combination of a pair of parallel bat forming chambers, feeding mechanism adapted to communicate with said chambers, a gate pivotally mounted between said chambers and adapted to close communication between either thereof and said feeding mechanism, and means for automatically operating said gate.
10. 2. In a hat forming machine, the combination of a pair of parallel bat forming chambers, feeding mechanism adapted to communicate with said chambers, a gate pivotally mounted between said chambers and automatically operating means common to both of said chambers whereby either thereof may be placed out of communication with said feeding mechanism.
15. 3. In a hat forming machine, the combination of a pair of parallel bat forming chambers, of feeding mechanism therefor, including a distributing roller and a distributing box in which said roller is journaled, and automatically operating means common to both of said chambers whereby either thereof may be placed out of communication with said feeding mechanism.
20. 4. In a hat forming machine, the combination of a pair of parallel closely adjacent bat forming chambers, a recessed plate horizontally positioned in each chamber and adapted to distribute uniformly the material supplied thereto, feeding mechanism communicating with said chambers and common to both thereof, means common to both said chambers whereby either thereof may be cut off from communication with said feeding mechanism, and means for automatically operating said last named means.
25. 5. In a hat forming machine, the combination of a pair of closely adjacent bat forming chambers each provided with a movable door, of feeding mechanism communicating with and common to both said chambers, automatically operating means whereby either of said chambers may be cut out of communication with said feeding mechanism, and connections between the doors of said chambers whereby the operation of the door of a chamber in one direction will positively operate the door of the adjacent chamber in an opposite direction, and whereby said means is operated to cut either of said chambers out of communication with said feeding mechanism.
30. 6. In a hat forming machine, the combination of a pair of closely adjacent parallel bat forming chambers, feeding mechanism common to and communicating with both of said bat forming chambers, a vertically slideable door on each bat forming chamber,

means pivoted between said chambers and common to both thereof for cutting either of said chambers out of communication with said feeding mechanism, and a flexible connection between said doors whereby the operation of one of said doors will operate the other door in a reverse direction and will also operate said means to cut either chamber out of communication with said feeding mechanism.

7. In a hat forming machine, the combination of a pair of closely adjacent parallel bat forming chambers, feeding mechanism common to both thereof and communicating therewith, a gate pivotally mounted between said chambers and automatically operative to cut either thereof out of communication with said feeding mechanism, spraying devices in each of the bat forming chambers, a sliding door forming a part of each bat forming chamber, and means carried by said sliding doors for rendering said spraying devices operative and inoperative respectively.

8. In a hat forming machine, the combination of a pair of closely adjacent parallel bat forming chambers, feeding mechanism common to both thereof and including a pair of feeding rollers, means adjacent said rollers for removing foreign matter therefrom, a gate pivotally mounted between said bat forming chambers and automatically operative to place either thereof out of communication with said feeding mechanism, doors slidably mounted on said bat forming chambers, and means whereby the operation of said doors causes the automatic operation of said gate.

9. In a hat forming machine, the combination of a pair of closely adjacent parallel bat forming chambers; a flexible connection between said chambers and pivotally mounted therebetween, feeding mechanism common to both said chambers, doors slidable on said bat forming chamber, a flexible connection between said doors, tappets carried by said flexible connection, means carried by the doors adapted to contact with said tappets whereby said doors are alternately operated, and means whereby certain of said tappets are adapted to actuate said gate.

In testimony whereof I affix my signature in presence of two witnesses.

JOSEF KOLB.
